UNITED STATES PATENT OFFICE.

GEORGE W. BUGBEE, OF DELHI, OHIO, ASSIGNOR TO THE J. A. FAY & EGAN COMPANY, OF CINCINNATI, OHIO.

PLANING AND MATCHING MACHINE.

SPECIFICATION forming part of Letters Patent No. 639,353, dated December 19, 1899.

Application filed March 6, 1899. Serial No. 707,884. (No model.)

To all whom it may concern:

Be it known that I, GEORGE W. BUGBEE, a citizen of the United States, residing at Delhi, in the county of Hamilton and State of Ohio, 5 have invented certain new and useful Improvements in Planing and Matching Machines, of which the following is a specification.

My invention relates particularly to that 10 class of planing and matching machines adapted to plane or match the edges of comparatively thin stock, such as is used in boxes, picture - backing, for making glue-joints, and for similar purposes.

15 My invention consists in providing a machine through which the stock may be fed on either straight or hollowing lines; further, in providing a machine adapted to take in and to feed through short pieces of stock, in feeding 20 the stock between continuous simultaneously-advancing feeding-faces, and in the various parts and in the arrangement and combinations of parts hereinafter more fully described and claimed.

25 In the drawings, Figure 1 represents a front elevation of my improved device. Fig. 2 is a plan view of the same with one pair of the feeding-chains omitted, and Fig. 3 is a side elevation of the same. Fig. 4 is a plan and 30 end view of a part of the chain and its guiding-plate; and Fig. 5 represents a side elevation, front, and bottom view of one of the chain-links.

A represents the frame of the machine, supporting brackets B B', carrying mandrels b b', mounted, preferably, at each end in bearings b² b³. The brackets slide in ways a on the frame of the machine and are adjusted by means of bolts a' a², rotatably secured against endwise 35 movement in lugs a³ a⁴ and taking into threaded projections b⁴ b⁵ on the brackets. The mandrels carry suitable cutter-heads C C', removably secured thereto, and suitable pulleys for operating the same. The cutter-heads C 40 C' are adapted to carry oppositely-arranged cutting agencies for cutting the meeting faces of two boards with interlocking joints. The cutter-heads operate, respectively, in a plane between each of the pair of feeding-chains 45 hereinafter mentioned, which latter feed the boards over the cutter-heads.

The material is fed through the machine between feeding-chains D D', consisting of a series of links d, having feeding-faces d', with hooks d² at one end taking about stems 55 d³ at the other end of the next succeeding link and arranged to slip about the stem through a recess d⁴ in the link. The feeding-faces are preferably integral with the chain-links, which latter I prefer to construct in a 60 single piece with their mutually-connecting parts in such manner as to be releasably connected, thus reducing the number of points of wear in the chain to the minimum, allowing any link to be readily removed, and producing a chain substantial in structure and efficient in operation. The chains D may take about sprocket-wheels d⁵ d⁶ and the chains D' take about sprocket-wheels d⁷ d⁸.

E is a shaft having pulleys e e to receive 70 power from any suitable source and carrying a suitable pinion e', meshing with a gear f on a shaft F. The shaft carries bevel-pinions f', rigidly secured thereto, meshing with bevel-gears f² on a shaft f³, journaled in the frame 75 and carrying the sprocket-wheels d⁷. The shaft F also has splined thereto bevel-gears f⁴, meshing with bevel-gears f⁵, mounted on a shaft f⁶, journaled in a slide G and carrying the sprocket-wheel d⁸.

80 The slide G is adjustable in ways a⁵ by means of a screw-shaft g, carrying a hand-wheel g'. The screw-shaft is tapped into a suitable lug on the slide G and passes loosely through a cap g². A spring g³ is preferably 85 interposed between the lug on the slide and the cap and yieldingly holds the slide and its attendant parts up to their work. The slide has a bearing g⁴ for a pivot g⁵ for a bracket H. A stud h takes into a slot h' in the bracket 90 and is adjusted therein by a bolt h² and secured in place by a nut h³. The sprocket-wheel d⁶ may be mounted on the stud. The bracket contains an opening h⁵ to allow for the removal and adjustment of the cutter-head 95 without interference with, obstruction by, or adjustment of any other part of the machine. The bracket also carries an extension h⁶ at, preferably, right angles to its length, through which a bolt h⁷ is adapted to pass into the 100 slide, a spring h⁸ being employed to force the swinging end of the bracket toward the stock

to be operated. The bolt h^2 carries an idler-roll h^9 , movable in a slot a^6 in an ear a^7 , bolted to the frame of the machine. The bracket H also carries a pendant H¹⁰, taking into an annular groove f^7 in the hub of the bevel-gear f^4 .

I I are brackets secured to the frame of the machine, carrying bearings i for the shafts f^3 , the shafts preferably having one of the bearings at each end. The sprocket-wheels d^7 are secured to the shafts f^3 . The brackets I also carry studs i^2 , on which the sprocket-wheels d^8 may rotate. Bolts i^3 take through the bracket and into the studs i^2 , adjusting the latter in the slots i^4 , wherein they may also be secured by means of nuts i^5 . By means of the adjustment of the studs h and i^2 proper tension is given to the feeding-chains. A set-screw i^5 is tapped into a lug a^8 and has a lock-nut i^6 . The set-screw i^5 takes against the free end of the bracket I and gives it adjustment and rigidity. The brackets H and I also preferably have guiding-plates K for the feeding-chains, secured thereto, preferably, by means of bolts k , taking through slots k' into the brackets. The guiding-plates carry suitable guides $k^2 k^3$ for grooves $d^9 d^{10}$ in the links.

L L' are tables carrying gages $l l'$, which may be secured thereto by means of bolts l^2 , taking through the slots l^3 into the table. The tables are also preferably secured to slides M M', sliding in brackets a^9 , adjustable by means of set-screws m and secured by means of set-bolts m' , taking through slots in the brackets into the slides. The connection and adjustment between the slides and tables is preferably secured by means of set-bolts $l^4 l^5$, taking through slots $l^6 l^7$ in the table, and by means of set-screws $l^8 l^9$, tapped into lugs $l^{10} l^{11}$, which may take against the lower edge of the table, giving it a pivotal adjustment.

In operation the stock to be operated upon is placed on a work-support N and thence fed into the machine. The work-support is placed conveniently between the two pairs of feeding-chains in such position that one operator may attend to both. The chain D' serves as the fixed face or gage to determine the line of cut. The gages $l l'$ are set to correspond to the chain D'. The tables may be set angling slightly upward toward the rear by means of the set-screws $l^8 l^9$, thus giving lead to the stock. If it be desirous to make a hollowing cut, the feeding-in table is set with its free end drooping and the feeding-out table may be correspondingly set with free end drooping.

In making glue-joints it is especially desirable to have the joint cut slightly hollow, so that the ends of the material after being glued together and properly pressed may form an intimate and lasting joint. My improved device is peculiarly well adapted for providing material with the desirable hollowing joint by simple means. The yielding slide G allows the machine to accommodate itself to stock of varying thickness of material, and the spring h^8 , acting on the free ends of the bracket H, allows the free end of the latter to act slightly

yieldingly on the stock when it enters between the feed devices and, with the spring g^3 , increases the pressure as the stock advances. 70 This construction insures the immediate positive gripping of the stock as soon as it comes in contact with the chains and the positive feeding of the material through the machine. As the stock advances toward the rear end 75 of the chains the tension on the spring h^8 increases, and when the tension of the spring h^8 is increased sufficiently to overcome the normal tension of the spring g^3 or is exhausted the latter spring is brought into play by the 80 slide G giving against the tension of the latter spring and the stock is held between the feeding-faces by the combined action of the springs h^8 and g^3 . It is desirable in presenting stock to be fed that the yield of the feeding-faces where they take hold of the stock shall be slight and the feeding-faces comparatively easily separated, but that the hold of the feeding-faces on the stock at the point where the cutter-head makes contact with the 85 stock shall be firm and rigid to resist the thrust of the cutter-head against the stock and maintain the latter in its proper relation to the cutter-head. I attain these objects by simple and effective devices. The stock is grasped 90 by moving feeding-faces from both sides at the same time, which carry it through the machine at a rapid rate of feed, the stock being relatively stationary to both its impacting feeding-faces while passing through the machine. The feeding-faces also form a substantially continuous moving feeding agency 95 on both sides of the stock, enabling extremely short pieces of, say, two to four inches in length to be fed through the machine at a rapid rate 100 of feed.

In my device the stock is fed through the machine on edge between two substantially continuous plane feeding-faces moving in unison above the acting cutter-head, operating in a vertical plane between the same in such way that one of the feeding-faces may serve as the gage or determine the line of travel of the stock and the line of cut on the same and the other yield pivotally and bodily 115 for the purposes stated and to variations in thickness of stock and hold the stock firmly between the feeding-faces, which latter present substantially continuous plane feeding-surfaces to both sides of the stock, with the stock moving relatively stationary to the latter between the same while it is being fed through the machine, with plane feeding-faces contacting against both its sides in a substantially continuous line, and with guiding-plates 120 for the feeding-faces maintaining the faces in a predetermined line of travel vertically and horizontally with relation to their supports when feeding the stock, thus preserving the stock in its true line of travel and in proper position in a very effective manner.

My improved device is very compact, and the peculiar construction, arrangement, and combinations of parts enable stock to be fed

through the machine at a very high rate of speed.

I claim—

1. In a planing and matching machine, the combination of four wheels having their axes in a vertical plane, and arranged in two pairs in a horizontal plane, a vertically-disposed series of flexible feeding-faces for traveling about each pair for feeding the material between them, on edge, a cutter-head operating in a vertical plane between the two series of flexible feeding-faces, means for advancing the faces in unison, a rigid support for one of the series of faces, a yielding support for the other, and a guiding-plate for each series of flexible faces, with means for the adjustment of the guiding-plate laterally on its support in a plane at substantially right angles to the axes of the wheels, and means for securing the guiding-plates rigidly with relation to their respective supports after adjustment, substantially as described.
2. In a planing and matching machine, the combination of four wheels having their axes in a vertical plane and arranged in two pairs in a horizontal plane, a vertically-disposed series of flexible feeding-faces for traveling about each pair for feeding the material between them, a cutter-head operating in a vertical plane between the two series of flexible feeding-faces, means for advancing the faces in unison, a rigid support for one of the series of faces, a yielding support for the other, and a rigid guiding-plate for the rigid support for the series of flexible feeding-faces thereon and vertically disposed between the wheels therefor, a vertically-disposed rigid guiding-plate on the yielding support for the series of flexible feeding-faces for the yielding support rigid with relation thereto and yielding therewith, with a connection between each series of flexible feeding-faces and its guiding-plate for maintaining the faces in a predetermined line of travel vertically and horizontally with relation to their supports when feeding the stock, and constructed and arranged for feeding the stock on edge over the cutter-head between two series of flexible feeding-faces, substantially as described.
3. In a planing and matching machine, the combination, of four wheels having their axes in a vertical plane and arranged in two pairs in a horizontal plane, a vertically-disposed series of flexible feeding-faces for traveling about each pair for feeding the material between them, with a cutter-head operating in a vertical plane between the two series of flexible feeding-faces, means for advancing the faces in unison, a rigid support for one of the series of faces, a laterally-yielding support for the other, and a guiding-plate for each of the series of flexible faces, with means for the adjustment of the guiding-plate on its support laterally in a plane at substantially right angles to the axes of the wheels, and means for securing the guiding-plates rigidly with relation to their respective sup-

ports after adjustment, and constructed and arranged for feeding the stock on edge over the cutter-head between the two series of 70 flexible feeding-faces, with parts for leading the stock to the cutter-head, substantially as described.

4. In a planing and matching machine, the combination, of four wheels having their axes in a vertical plane and arranged in two pairs in a horizontal plane, a vertically-disposed series of flexible feeding-faces for traveling about each pair for feeding the material between them, a cutter-head operating in a vertical plane between the two series of flexible feeding-faces, means for advancing the faces in unison, a slide for supporting one of the series of flexible feeding-faces, means for positively adjusting the slide toward and 80 away from the other series with a spring or similar means for giving the slide a yielding pressure, a bracket pivoted with relation to the slide and moving therewith and a spring or similar means for giving a yielding pivotal 85 pressure to the outer end of the bracket, combined for imparting to the stock an increasing pressure between the feeding-faces as it advances toward the cutter-head, and constructed and arranged for feeding the stock 90 on edge over the cutter-head between the two series of flexible feeding-faces, substantially as described.

5. In a planing and matching machine, the combination of four wheels having their axes in a vertical plane and arranged in two pairs in a horizontal plane, a vertically-disposed series of flexible feeding-faces for traveling about each pair for feeding the material between them, a cutter-head operating in a vertical plane between the two series of flexible feeding-faces, means for advancing the faces in unison, a slide for supporting one of the series of flexible feeding-faces, means for positively adjusting the slide toward and 100 away from the other series, with a spring or similar means for giving the slide a yielding pressure, a bracket pivoted with relation to the slide and moving therewith and a spring or similar means for giving a yielding pivotal 105 pressure to the outer end of the bracket, combined for imparting to the stock an increasing pressure between the feeding-faces as it advances toward the cutter-head, and constructed and arranged for feeding the stock 110 on edge over the cutter-head between the two series of flexible feeding-faces, substantially as described.

6. In a planing and matching machine, the combination of four wheels having their axes in a vertical plane and arranged in two pairs in a horizontal plane, a vertically-disposed series of flexible feeding-faces for traveling about each pair for feeding the material between them on edge, a cutter-head operating in a vertical plane between the two series of flexible feeding-faces, means for advancing the feeding-faces in unison, a rigid support

- for one of the series of faces, a sliding support for the other, means for positively adjusting the sliding support laterally toward and away from the rigid support, a spring or similar means for giving the sliding support a laterally-yielding pressure, a bracket pivoted with relation to the sliding support and moving therewith, and a spring or similar means for imparting a pivotally-yielding pressure to the outer end of the bracket, and a guiding-plate for each series of flexible feeding-faces, with means for the adjustment of each guiding-plate on its support laterally in a plane at substantially right angles to the axes of the wheels, means for securing the guiding-plates rigidly with relation to their respective supports after adjustment, with a connection between each series of flexible feeding-faces and its guiding-plate for maintaining the faces in a predetermined line of travel vertically and horizontally with relation to their supports when feeding the stock, substantially as described.
7. In a planing and matching machine, the combination of four wheels having their axes in a vertical plane and arranged in two pairs in a horizontal plane, a vertically-disposed series of flexible feeding-faces for traveling about each pair for feeding the material between them on edge, a cutter-head operating in a vertical plane between the two series of flexible feeding-faces, means for advancing the feeding-faces in unison, a rigid support for one of the series of faces, a sliding support for the other, means for positively adjusting the sliding support laterally toward and away from the rigid support, a spring or similar means for giving the sliding support a laterally-yielding pressure, a bracket pivoted with relation to the sliding support and moving therewith, and a spring or similar means for imparting a pivotally-yielding pressure to the outer end of the bracket, with an opening h^5 in the bracket for the removal of the cutter-head, and a guiding-plate for each series of flexible feeding-faces, with means for the adjustment of each guiding-plate on its support laterally in a plane at substantially right angles to the axes of the wheels, means for securing the guiding-plates rigidly with relation to their respective supports after adjustment, with a connection between each series of flexible feeding-faces and its guiding-plate for maintaining the faces in a predetermined line of travel vertically and horizontally with relation to their supports when feeding the stock, substantially as described.
8. In a planing and matching machine, the combination of four wheels having their axes in a vertical plane and arranged in two pairs in a horizontal plane, a vertically-disposed series of flexible feeding-faces for traveling about each pair for feeding the material between them on edge, each comprising an endless feeding-chain consisting of a series of releasable chain-links having their mutual con-

nnections integral with themselves with vertically-disposed flat feeding-faces integral with the links, and constructed and arranged to form two substantially continuous plane feeding-surfaces and acting interdependently upon the stock being fed, with means for advancing the feeding-faces in unison, and parts for leading the stock to the cutter-head, and constructed and arranged for feeding short pieces of stock of say two to four inches in length over the cutter-head with the plane vertical feeding-faces advancing relatively stationary with the stock being fed, a rigid support for one of the series of feeding-faces, a sliding support for the other, means for positively adjusting the sliding support toward and away from the rigid support, with a spring or similar means for giving the sliding support a yielding pressure, a guiding-plate for each series of flexible feeding-faces, with a connection between each series of flexible feeding-faces and its guiding-plate for maintaining the faces in a predetermined line of travel vertically and horizontally with relation to their supports when feeding the stock, substantially as described.

9. In a planing and matching machine, the combination of four wheels having their axes in a vertical plane and arranged in two pairs in a horizontal plane, a vertically-disposed series of flexible feeding-faces for traveling about each pair, the slide G, screw-shaft g , and a spring for yieldingly holding one of the flexible feeding-faces up to its work bodily, with the bracket H and its extension h^6 pivotally hung on the slide, and the spring h^8 for permitting the yielding of the bracket on its pivot, substantially as described.

10. In a planing and matching machine, the combination of four wheels having their axes in a vertical plane and arranged in two pairs in a horizontal plane, a vertically-disposed series of flexible feeding-faces for traveling about each pair, with a bracket I and an adjustable stop i^5 for the outer end of the bracket for one of the series of flexible feeding-faces, and a slide G, a screw-shaft g , and a spring, for yieldingly holding the other of the flexible feeding-faces up to its work bodily, with a bracket H and an extension h^6 pivotally hung with relation to the slide and moving therewith, and a spring h^8 for permitting the yielding of the bracket on its pivot, substantially as described.

11. In a planing and matching machine the combination of four wheels having their axes in a vertical plane and arranged in two pairs in a horizontal plane, a vertically-disposed series of flexible feeding-faces for traveling about each pair, a slide G, a screw-shaft g , and a spring for yieldingly holding one of the flexible feeding-faces up to its work bodily, with a bracket H and an extension h^6 pivotally hung with relation to the slide and moving therewith, a spring h^8 for permitting the yielding of the bracket on its pivot, a guide-

way a^6 for the outer end of the bracket, and a part on the bracket taking into the guideway, substantially as described.

12. The combination, in a planing and matching machine, of a pair of vertically-disposed series of flexible feeding-faces arranged in juxtaposition in a horizontal plane, and acting interdependently for feeding the material past the cutting agency, a cutting agency operating in a vertical plane between

the faces, an independent table on each side of the cutter-head extending in the plane of the feed, and means for setting the tables to droop the outer ends of the tables for imparting a hollowing cut to the stock, substantially as and for the purpose specified. 15
